UNITED STATES PATENT OFFICE.

ROBERT BRUCE MITCHELL, OF HOMESTEAD, PENNSYLVANIA, ASSIGNOR OF ONE-EIGHTH TO JOHN B. MITCHELL, FIVE-SIXTEENTHS TO EDWARD C. MCKINNEY, AND ONE-FOURTH TO PETER A. MCKINNEY, ALL OF HOMESTEAD, PENNSYLVANIA.

BOTTLEHOLDER.

Application filed September 1, 1922. Serial No. 535,755.

To all whom it may concern:

Be it known that I, ROBERT B. MITCHELL, a citizen of the United States, and a resident of Homestead, in the county of Allegheny and State of Pennsylvania, have invented certain new and useful Improvements in Bottleholders, of which the following is a specification.

This invention relates to an improvement in bottle holders especially, although not necessarily, adapted for use with milk bottles, and the object of the invention is to provide a bottle holder with which a bottle may be readily associated or from which it may readily be taken and which at the same time positively and securely supports the bottle suspended free of contact with surrounding structures, the mouth of the bottle and the associated parts thereof being housed and protected so as to be preserved in a clean and sanitary condition.

A further object is to provide a bottle holder of this character which is so constructed and organized as to lend itself to a convenient mode of manufacture from materials and with facilities ordinarily available and which is of simple and durable construction, reliable in use and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, showing the preferred embodiment of the invention;

Figure 2 is a view thereof in central vertical section;

Figure 3 is a view in horizontal section, taken approximately on line 3—3 of Figure 1; and

Figure 4 is a detail view in section, taken approximately on line 4—4 of Figure 1.

Referring to the drawings, the numeral 10 designates a portion of the permanent structure or support upon which the bottle holder is mounted. The bottle holder includes a horizontally extending bracket 11 comprising a body portion or supporting plate 12 recessed or cut away, as at 13, to

accommodate the neck of the bottle, the rim 55 of the neck of the bottle extending over the edge of the supporting plate 12 to provide for the support of the bottle. The plate 12 is provided along its side edges with vertical flanges 14, the other ends of which are 60 inturned, as shown in Figures 3 and 4, the flanges extending for the full length of the plate 12 and consequently being somewhat elongated. The outer end portions of the plate 12 on each side of the recess 13 are 65 provided with upstanding or vertical flanges 16 which are extended up around and folded back upon the inturned end portions 15 of the flanges 14, this arrangement serving to brace and strengthen both the flanges 14 and 70 16. The bracket 11 also includes an attaching plate 17 integrally formed with the plate 12 and depending at right angles therefrom.

A cover or top member is provided for the bottle holder and includes a top plate 18 75 having its end deflected upwardly, as at 19, and integrally formed at its inner end with an attaching plate 20. The top plate 18 engages the top edges of the flanges 14 and 16 and the attaching plate 20 is disposed flush 80 against the support 10 whereas the attaching plate 17 of the bracket 11 is disposed flush against the attaching plate 20. With this arrangement of the attaching plates common fastening means is employed for 85 securing the holder to the support 10, such fastening means preferably comprising screws, nails or the like inserted through suitable openings provided in the attaching plates and engaged with the support. The 90 cover or top member is constructed of resilient sheet steel or other material having the desired resiliency and flexibility and the bracket 11 is preferably constructed of rolled metal plate. 95

In use, when a bottle is to be placed in the holder the rim of the bottle is engaged with the upwardly deflected end 19 of the top plate and the top plate is sprung upwardly, as indicated in dotted lines in Figure 2 in 100 order that the neck of the bottle may be moved into the holder. In the holder the neck of the bottle is accommodated in the recess 13 and the rim of the neck is engaged with the edge of the supporting plate 12 105 and of course the top 18 is sprung back into engagement with the top edges of the flanges 14 and 16 so as to completely house and pro-

tect the top of the bottle and preserve it in a clean, sanitary condition. It is to be noted that the flanges 14 and 16 not only serve to house and protect the bottle but also serve 5 to strengthen or support the supporting plate 12 by which the bottle is held suspended and out of contact with any solid structure or any place upon which germs, dust or the like are not liable to accumulate and result in 10 contamination of the bottle.

As shown the bottle holder is constructed of two pieces of metal but obviously it may be advantageously constructed of a single piece of metal folded along the line of the 15 lower edges of the attaching plates 17 and 20.

I claim:

1. A bottle holder including a bracket comprising a supporting plate having a recess 20 adapted to accommodate the neck of the bottle, the edges of the supporting plate around said recess being engageable with the rim of the bottle, side flanges integrally formed with the supporting plate and up- 25 standing vertically therefrom, end flanges integrally formed with the outer end portions of the supporting plate and interengaged with the side flanges said bracket having an attaching plate integral with the sup- 30 porting plate, and a top member comprising a resilient top plate engageable with the top edges of the side and end flanges, said top plate having its outer edge upwardly deflected and having an attaching plate in- 35 tegally formed therewith, the attaching plate of the bracket and top member being

engaged and being adapted to coact with common fastening means for securing the bottle holder in position.

2. A bottle holder comprising a bracket 40 having a recessed supporting plate, the recess accommodating the neck of the bottle and the edge of the supporting plate around the recess being engageable with the rim of the bottle to support the same, said supporting plate having upstanding flanges for housing the bottle and a spring top plate engageable with the flanges to cover the top of the bottle, the top plate being movable away from the flanges to permit of the placing of the bottle within the holder and the removal of the bottle therefrom.

3. A bottle holder comprising a bracket having a recessed supporting plate, the recess extending from the outer edge of the 55 supporting plate inwardly thereof and being adapted to accommodate the neck of the bottle, the edge of the supporting plate around the recess being engageable with the rim of the bottle to support the same, said supporting plate having upstanding flanges for housing the bottle and a top plate engageable with the flanges to cover the top of the bottle and coacting with the flanges and with the supporting plate to completely 60 enclose the top of the bottle, the top plate being movable away from the flanges to permit of the placing of the bottle into the holder and the removal of the bottle therefrom.

ROBERT BRUCE MITCHELL.
